(57) **ABSTRACT**

Disclosed herein is a device comprising a pulse trigger switch module configured to generate a first control signal in response to a first input signal value and generate the second control signal in response to a second input signal value. An on pulse generator module provides a first pulse signal having a first predetermined pulse duration in response to the first control signal and an off pulse generator module provides a second pulse signal having a second predetermined pulse duration in response to the second control signal. An on pulse switch module connects a power signal to an output in response to the first pulse signal and an off pulse switch module connects the power signal to the output in response to the second pulse signal.

PULSE SOLENOID CONTROL CIRCUIT

CROSS-REFERENCE TO RELATED
APPLICATIONS

This application is a continuation of U.S. patent application Ser. No. 14/644,364 (now U.S. Pat. No. 9,786,458), filed on Mar. 11, 2015, titled "Pulse Solenoid Control Circuit," which claims the benefit of U.S. provisional application No. 61/954,180, filed on Mar. 17, 2014, titled "Pulse Solenoid Control Circuit," which is incorporated herein by reference. To the extent appropriate, a claim for priority is made to each of the above-identified applications.

TECHNICAL FIELD

The present disclosure relates generally to a system and method for controlling a latching solenoid, and, in particular embodiments, to a system and method for a solenoid control circuit that generates a pulsed control signal for a latching solenoid.

BACKGROUND

In the design of solenoids having latching coils there is a specified direct current (VDC) required to both latch ON and latch OFF the coil, thus either opening or closing the solenoid valve. We will assume that the coil is 12 VDC. Therefore, a 12 VDC current would be required to latch ON or open the solenoid valve. However, since the coil is of a latching nature, there is no need for continuous current to energize the coil. The basic principle of the latching coil is that a magnetic draw is present at both the open and closed positions of the coil. The VDC current applied to the coil increases the magnetic draw at the open end thus drawing the piston of the solenoid body towards the upper end of the coil or open position. By inverting this VDC current the magnetic draw is reversed, thus moving the piston of the relay to the lower or closed position. In both the on and off positions, the coil will maintain the piston's position without the need of continuous current.

A Programmable Logic Controller (PLC) or similar device cannot typically be programmed to transmit a brief voltage signal to the solenoid coil in order to latch on the solenoid valve and then transmit an inverted signal to latch off the valve. A continuous signal creates excess heat at the coil and unneeded energy expense.

BRIEF DESCRIPTION OF THE DRAWINGS

For a more complete understanding of the present embodiments, reference is now made to the following descriptions taken in conjunction with the accompanying drawings, in which:

FIG. 1 is a logical diagram of a pulse solenoid control circuit according to an embodiment;

FIG. 2 is a circuit diagram illustrating an embodiment of a pulse solenoid control circuit; and

FIG. 3 is a diagram illustrating signals during operation of a pulse solenoid control circuit according to an embodiment.

Corresponding numerals and symbols in the different figures generally refer to corresponding parts unless otherwise indicated. The figures are drawn to illustrate the relevant aspects of the embodiments and are not necessarily drawn to scale. For clarity non-essential reference numbers are left out of individual figures where possible.

DETAILED DESCRIPTION OF ILLUSTRATIVE
EMBODIMENTS

The making and using of the present embodiments are discussed in detail below. It should be appreciated, however, that the present disclosure provides many applicable concepts that can be embodied in a wide variety of specific contexts. The specific embodiments discussed are merely illustrative of specific ways to make and use the disclosed subject matter, and do not limit the scope of the different embodiments.

It has been discovered that a brief pulse signal is the best means of providing the needed current to latch ON and OFF for a solenoid valve. Presented herein is a circuit board that 15 enables a continuous output signal to be converted into a brief direct current signal to permit a solenoid valve with a direct current latching coil to open and close as determined by the polarization of the direct current signal. The embodiments presented herein are directed to providing a circuit 20 that generates a first pulse to turn on or activate a solenoid and a second pulse to turn off or deactivate the solenoid. In some embodiments, the circuit will provide no power between pulses, reducing the power required to control the solenoid. The pulses are generated in response to an input 25 signal. The pulses are generated on the transition of the input signal, with the circuit generating a pulse when the input signal switches from an off state to an on state, and generating a pulse when the input signal switches from the on state to the off state.

30 FIG. 1 illustrates a logical diagram of a pulse solenoid control circuit according to an embodiment. Output pulses are provided to an output 116 to control the activation or deactivation of an electrically controllable switch. The load 118 is activated, or turned on, with an output on pulse of a limited or predetermined duration. Additionally, the load 118 is deactivated, or turned off, with an output off pulse. In some embodiments, the output off pulse has a polarity that is the opposite of the polarity of the output on pulse. Additionally, the load 118 latches on or off, remaining 35 activated or deactivated after the output on pulse or output off pulse terminates and until the state is reversed with another output on pulse or output off pulse. The load 118 at the output 116 is described as a load solenoid/relay, however it should be understood that a solenoid type relay, a solenoid, 40 a relay or another electrically activated switch that can be used as a load 118.

An input signal Vin is received at a switch control module 102. The switch control module 102 controls a pulse trigger switch module 104, which in turn activates an on pulse 45 generator module 108 or an off pulse generator module 106. The switch control module 102 generates a switch control signal to toggle the pulse trigger switch module 104 to provide a control signal to either the off pulse generator module 106 or the on pulse generator module 108. When the 50 on pulse generator module 108 or the off pulse generator module 106 receives a control signal from the pulse trigger switch module 104, the respective pulse generator module 106 and 108 generates a pulsed signal of a predetermined duration, which is transmitted to a respective on pulse switch module 112 or an off pulse switch module 114. The pulse switch modules 112 and 114 are activated by the pulse signal from the pulse generator modules 106 and 108 and connect the power supply 110 to the load solenoid/relay 118 through the output 116. The on pulse switch module 112 and the off 55 pulse switch module 114 connect the power supply 110 voltage or signal to the output 116 and load solenoid/relay 118 during the on or off pulse, respectively, resulting in a

single output signal with a pulse at both the on and off time periods. In some embodiments, the pulse switch modules **112** and **114** provide pulses of opposite polarity to the output **116**, but can also be arranged to provide pulses of a same polarity to the output **116**.

FIG. 2 is a circuit diagram illustrating an embodiment of a pulse solenoid control circuit. In some embodiments, the input signal V_{in} is a 24 VAC input signal that is connected to the switch control module **102** at connector CON2. The printed circuit board "PCB" will accept a 24 VAC input signal V_{in} at the switch control module **102** and then pulse ON a double pole double throw relay **U8**, which in turn provides a momentary 12 VDC operating signal to the output **116** latch ON the solenoid of the load/relay **118**. When the input signal V_{in} is withdrawn or turned off then an inverted momentary 12 VDC signal is provided for example, by a second double pole double throw relay **U7**, to the output **116** and unlatches or turns OFF the solenoid of the load/relay **118**. In other embodiments, the switch control module **102** is configured to receive a DC signal, such as from a programmable logic controller, microprocessor, relay, battery, switch, circuit, or the like.

Providing, for example, a 12 VAC or 24 VAC current to the power supply **110** at connector CON1 will provide the current to bridge rectifier **U2** converting that current to VDC. Voltage regulator **U3**, resistor **R3**, capacitor **C2**, and capacitor **C3** provide the power regulation for the 12 VDC needed to latch the solenoids. Resistor **R16**, diode **D4** and diode **D5** provide the needed voltage separation between current to permit a battery to be connected at connector CON4.

The battery provides 12 VDC and will charge from available current and provide a backup source of power to unlatch the solenoid(s) connected to output connector CON3 in the event of a power failure. Though not needed in all applications, this backup power source can in specific instances prove important.

The pulse trigger switch module **104** has a switch such as relay **U4** that provides a first control signal in response to a first input signal value for V_{in} and a second control signal in response to a second input signal value for input signal V_{in} . The pulse trigger switch module **104** causes the on pulse generator module **108** to generate an on pulse signal in response to the input signal V_{in} being turned on, and causes the off pulse generator module **106** to generate an off pulse signal in response to the input signal V_{in} being turned off. For example, routing the input signal V_{in} through bridge rectifier **U1** and additional circuitry including capacitor **C1**, resistors **R1** and **R2**, LED **LED1**, and diode **D1** provides a 12 VDC switch control signal to the pulse trigger switch module **104** that enables relay **U4** of the pulse trigger switch module **104** to operate or switch to an ON state, transmitting the 12 VDC control signal to the on pulse generator module **108**.

The on pulse generator module **108** generates an on pulse control signal in response to the on input signal, or where the input signal V_{in} has an on value. The on pulse control signal has a pulse duration of a predetermined period that is controlled by timer **U6**. In some embodiments the timer **U6** is, for example, an NE555 timer that controls the pulse duration of the on pulse control signal. At timer **U6**, resistors **R14** and **R15** and capacitor **C9** provide a ground signal that triggers the ON state of the timer **U6** at pin 2. Once ON, the timer **U6** output at pin 3 will go HIGH (+VDC). Resistor **R13** and the base of transistor **Q2** provided the ground signal to relay **U8**. LED **LED3** indicates this process occurs. The ground signal will only occur for a period required for the

voltage drop across pins 6 and 7 of the timer **U6** to hit the threshold whereby a ground signal occurs from pin 7 to pin 6 (Discharge). Resistors **R6** and **R7** and Capacitor **C6** provide this circuitry. Jumper post **2** allows a change between resistances of resistors **R6** and **R7** to modify the duration of the on pulse generated by the timer **U6**. The other pins on this timer **U6** are pin 1 which is ground, pin 8 which is +VDC, pin 5 which is control and is connected to ground through capacitor **C7**, and pin 4 which is reset and that is connected to +VDC through resistor **R12**.

The on pulse switch module **112** is configured to connect a power signal from the power supply **110** to the output **116** in response to the on pulse control signal. In some embodiments, the relay **U8** connects the power supply voltage to the output **116** during the on pulse control signal to provide an output on pulse to the output **116** to turn on or latch the load solenoid/relay **118**. Since the ground on pulse control signal ground from the timer **U6** is brief, contacts at relay **U8** remain closed only briefly. However, the ground on pulse control signal from the timer **U6** has the predetermined duration to provide adequate time for the load solenoid/relay **118** to switch an ON state. The duration of the on pulse control signal is independent from, and can longer or shorter than, the duration of the input signal V_{in} or than the duration of the input control signals from the pulse trigger switch module **104**. This results in an output on pulse from relay **U8** with a duration that permits switching on of the load relay **118** while conserving energy after the load relay **118** has been activated by terminating power to the relay when not needed for switching. The VDC and ground signals at input pins transmit through the normally open contacts to the normally closed contacts at relay **U7**. These signals are then conveyed through the input pins on this relay to output pins at connector CON3. Metal oxide varistor **MOV1** provides current stability at the output to the latching solenoid by protecting the circuit against excessive transient voltages. Diode **D3** provides flyback protection to the circuit at the relay **U8** coil.

The off pulse generator module **106** generates an off pulse control signal in response to the off input signal, or where the input signal V_{in} has an off value. The off pulse control signal having a pulse duration of a predetermined period controlled by timer **U5**. The circuitry, functionality and components of off pulse generator module **106** are, in some embodiments, substantially the same as for on pulse generator module **108** and timer **U6**. In some embodiments the timer **U5** is, for example, an NE555 timer, with timer **U5** activated when the input signal V_{in} is switched off and timer **U6** activated when the input signal V_{in} is switched on.

The off pulse switch module **112** is configured to connect a power signal from the power supply **110** to the output **116** in response to the off pulse control signal from the off pulse generator module. In some embodiments, the relay **U7** connects the power supply voltage to the output **116** during the off pulse control signal to provide an output off pulse to the output **116** to turn off or unlatch the load relay **118**. Once the 24 VAC input signal V_{in} is withdrawn at Connector CON2, relay **U4** opens, thus diverting the 12 VDC switch control signal to the circuitry at timer **U5**.

Note that the normally open output pins at relay **U7** are reversed from those of the normally closed pins of relay **U7**. This means that the ground derived from the output pin on **U8** is opposite the ground at relay **U7** and that the VDC is likewise opposite. Thus when the ground signal from Timer **U5** energizes the relay **U7**, a current having an opposite polarity is transmitted to these same output pins at connector CON3. Additionally, since the output of relay **U8** in the on

pulse switch module 112 is connected to the normally closed pins of relay U7 in the off pulse switch module 114, the output of U8 is transmitted to connector CON3 when the relay U7 is not activated. Activation of relay U7 interrupts the signal from relay U8 and transmits the output off pulse. Thus, the off pulse switch module 114 passes on the signal from the on pulse switch module 112, but overrides the signal from the on pulse switch module 112, allowing the load relay 118 to be turned off during turn-on phase. In other embodiments, the on pulse switch module 112 is arranged to pass on and override the signal from the off pulse switch module 114.

Also shown on FIG. 2 are two additional output pins at connector CON3 along with varistor MOV2. This allows 12 VDC devices that do not require the latching ON or OFF to be connected to the 12 VDC power supply of the PCB. In essence, the first signal introduced is polarized to latch ON the solenoid coil, thus opening the valve attached to the solenoid. The second signal is of opposite polarity, latching OFF the coil and closing the valve.

In the embodiment disclosed in FIG. 2, relays U7 and U8 are shown as controlling the pulse of the power supply 110 voltage to generate output pulses at output 116. However, the relays U7 and U8 are not limited strictly to any particular type of relay or switch. Any electrically triggered switch or combination of switches may be used to generate the output pulses. For example, a transistor, solenoid, digital switch, switching circuit, contactor, dry contact, or other electrically controlled mechanical switch may be employed.

FIG. 3 is a diagram illustrating signals during operation of a pulse solenoid control circuit according to an embodiment. The input signal Vin is switched from off to on, and the on pulse generator is activated. An on pulse is generated and the output Von of the on pulse generator causes the on pulse switch to connect the power supply voltage to the output Vout, resulting in a positive on pulse at Vout. The positive on pulse at Vout turns on or activates a load relay. When the input signal Vin is turned off, the transition from on to off causes the off pulse generator to generate an off pulse at the off pulse generator output Voff. The off pulse causes off pulse switch to connect the power supply voltage to the off pulse generator output Voff, resulting in an output off pulse that turns the load relay off. The Vout line of FIG. 3 illustrates the overall output signal, with the first output pulse having a first polarity and a timing and duration corresponding to the on pulse Von. The Vout line also has an off pulse with a negative polarity and a timing and duration corresponding to the off pulse Voff.

In an embodiment, where the off pulse is inverted, the output Voff has a negative off pulse. However, the embodiments disclosed herein are not limited to such an arrangement. Depending on the type of load relay or load relay configuration, a positive off pulse may be output. In such an arrangement the off pulse switch and the on pulse switch may be arranged in parallel instead of in series as shown in FIG. 2. Additionally, the pulses in Vout may have a different magnitude than the pulses generated by the pulse generators, since the pulse generators generate signals controlling the relays or other switches.

Thus, according to an embodiment, a device comprises a pulse trigger switch module configured to generate a first control signal in response to a first input signal value and generate the second control signal in response to a second input signal value. An on pulse generator module provides a first pulse signal having a first predetermined pulse duration in response to the first control signal and an off pulse generator module provides a second pulse signal having a

second predetermined pulse duration in response to the second control signal. An on pulse switch module connects a power signal to an output in response to the first pulse signal and an off pulse switch module connects the power signal to the output in response to the second pulse signal. A switch control module is configured to receive an input signal having at least the first input signal value or the second input signal value. The switch control module is configured to generate a switch control signal based on the input signal, and the input switch control module is further configured to transmit the switch control signal to the pulse trigger switch module. The pulse trigger switch module comprises a first switch configured to generate the first control signal in response to an input signal being turned on and further configured generate the second control signal in response to the input signal being turned off. In some embodiments, the input signal is an alternating current (AC) signal and wherein the first control signal is a direct current (DC) signal. The on pulse generator comprises a first timer generating the first pulse signal with a first duration independent of a duration of the first control signal and the off pulse generator comprises a second timer generating the second pulse signal with a second duration independent of a duration of the second control signal. First circuitry is disposed at the first timer and is configured to adjust the first duration, and second circuitry is disposed at the second timer and is configured to adjust the second duration. An output of the on pulse switch module is connected through normally closed contacts at the off pulse switch module and the off pulse switch module is configured to override an output signal from the on pulse switch module when the off pulse switch module is activated. In some embodiments, the on pulse switch module provides a first output pulse having a first polarity where the first output pulse is provided to the output by connecting the power signal to the output for a predetermined period of time. The off pulse switch module provides a second output pulse having a second polarity to the output where the second output pulse is provided by connecting the power signal to the output for a predetermined period of time. In such embodiments, the first polarity is different from the second polarity.

In other embodiments, a device comprises a first switch configured to provide a first control signal in response to a first input signal value and a second control signal in response to a second input value. A first timer is connected to the first switch and is configured to generate a first pulse signal in response to the first control signal and a second timer is connected to the first switch and is configured to generate a second pulse signal in response to the second control. A first relay is connected to the first timer and is configured to connect a power supply to an output during the first pulse signal and a second relay is connected to the second timer and configured to connect the power supply to the output during the second pulse signal. A switch control module is configured to receive an input signal and generate a switch control signal that causes the first switch to generate the first and second control signals based on a value of the input signal. In some embodiments, the input signal is an alternating current (AC) signal and the switch control signal is a direct current (DC) signal. The first timer generates the first pulse signal with a first duration independent of a duration of the first control signal and the second timer generates the second pulse signal with a second duration independent of a duration of the second control signal. In some embodiments, an output of the second relay is connected through normally closed contacts at the first relay and the first relay is configured to override an output pulse signal

from the output of the second relay when the first relay is activated. The first relay provides a first output pulse to the output by connecting the power supply to the output for a predetermined period of time and the second relay provides a second output pulse to the output by connecting the power supply to the output in a reversed polarity arrangement for a predetermined period of time. A load is connected to the output, and the load is configured to latch on in response to the first output pulse and to latch on in response to the second output pulse.

A method of controlling an electrically latching load according to an embodiment comprises receiving a switch control signal at a pulse trigger switch module and providing, with the pulse trigger switch module, an on input signal to an on pulse generator module when the switch control signal is in an on state and providing, with the pulse trigger switch module, an off input signal to an off pulse generator module when the switch control signal is in an off state. An on pulse control signal is generated with the on pulse generator module in response to the on input signal, the on pulse control signal having a pulse duration of a predetermined period. An off pulse control signal is generated with the off pulse generator module in response to the off input signal, the off pulse control signal having a pulse duration of a predetermined period. An output on pulse is provided to an output with the on pulse switch module by connecting a first power supply signal to the output in response to the on pulse control signal and an output off pulse is provided to the output with the off pulse switch module by connecting a second power supply signal to the output in response to the off pulse control signal. The output on pulse has a polarity different than the output off pulse. In some embodiments, a load is activated with the output on pulse and the load is deactivated with the output off pulse. A duration of the output on pulse is different than a duration of the on input signal. Providing an output on pulse comprises providing the output on pulse to the output through the off pulse switch module.

While the disclosed embodiments have been described with reference to illustrative embodiments, this description is not intended to be construed in a limiting sense. Various modifications and combinations of the illustrative embodiments, as well as other embodiments of the presented principles, will be apparent to persons skilled in the art upon reference to the description. It is therefore intended that the appended claims encompass any such modifications or embodiments.

What is claimed is:

1. A method for controlling an electrically latching load, the method comprising:
 receiving a switch control signal in an on state;
 providing an on input signal in response to receiving the switch control signal in the on state;
 generating an on pulse control signal in response to the on input signal, the on pulse control signal having a first pulse duration;
 in response to the on pulse control signal, providing an output on pulse to an output, wherein the output on pulse is configured to cause the electrically latching load to latch in an on position;
 receiving a switch control signal in an off state;
 providing an off input signal in response to receiving the switch control signal in the off state;
 generating an off pulse control signal in response to the off input signal, the off pulse control signal having a second pulse duration, wherein at least one of the first pulse duration and the second pulse duration are adjust-

able duration based on an adjustable resistance configured to be adjusted by a jumper; and
 in response to the off pulse control signal, providing an output off pulse to the output.

5 2. The method of claim 1, wherein the first pulse duration and the second pulse duration are the same.

3. The method of claim 1, wherein the on pulse control signal causes a power supply signal to be provided to the electrically latching load.

10 4. The method of claim 1, wherein the duration of the first pulse duration and the second pulse duration are independent of a duration of the switch control signal.

15 5. A method for controlling a load, the method comprising:

receiving a switch control signal in an on state, wherein the switch control signal is a continuous signal;
 based on receiving the switch control signal in the on state, generating an output on pulse, the output on pulse configured to activate the load; and
 upon cessation of receiving the switch control signal in the on state, automatically generating an output off pulse, the output off pulse configured to deactivate the load.

20 25 6. The method of claim 5, wherein the load is an electrically latching load.

7. The method of claim 5, wherein the output on pulse causes a power supply voltage to be connected to the load.

30 8. The method of claim 5, wherein the output on pulse has a polarity opposite a polarity of the output off pulse.

9. The method of claim 5, wherein the switch control signal is based on an input signal.

35 10. The method of claim 9, wherein the input signal is an alternating current signal and the switch control signal is a direct current signal.

11. The method of claim 10, wherein the switch control signal is a rectified form of the input signal.

40 12. An apparatus for controlling a load, the apparatus comprising:

a switch control module configured to provide a switch control signal in an on state, wherein the switch control signal is a continuous signal; and
 circuitry configured to:

generate an output on pulse generated on receiving the switch control signal in the on state, the output on pulse configured to activate the load; and
 automatically generating an output off pulse upon cessation of receiving the switch control signal in the on state, the output off pulse configured to deactivate the load.

55 13. The apparatus of claim 12, wherein the output on pulse causes a power supply voltage to be connected to the load.

14. The apparatus of claim 12, wherein the output on pulse has a first polarity and the output off pulse has a second polarity, the first polarity being opposite the second polarity.

15. The apparatus of claim 12, wherein the circuitry includes an on pulse generator module and an off pulse generator module.

60 16. The apparatus of claim 15, wherein the on pulse generator module includes a first timer and the off pulse generator module includes a second timer.

17. The apparatus of claim 12, further comprising a load configured to latch in an on position based on receipt of the output on pulse and to latch in an off position based on receipt of the output off pulse.

18. The apparatus of claim **12**, wherein the circuitry further includes a first pulse switch module and a second pulse switch module.

19. The method of claim **18**, wherein the output on pulse and the output off pulse each have a predetermined duration. 5

20. The apparatus of claim **12**, wherein the switch control module is configured to provide a switch control signal in an on state based on receiving an input signal.
